FULL FASHIONED KNITTING MACHINE

Rudolph Anke, Reading, Pa., assignor to Textile
Machine Works, Wyomissing, Pa., a corpora-
tion of Pennsylvania

Application February 28, 1930, Serial No. 432,023

19 Claims. (Cl. 66—129)

This invention relates to straight or full-fashioned knitting machines, and generally to the thread-feeding and stop-control mechanisms thereof, the primary object being to provide for 5 full automatic selective pattern controlled operation of the feed traverse of the several threads employed to produce almost any predetermined variety of plain or ornamental fabric.

With the above object in view, this invention 10 relates more specifically to automatic pattern controlled mechanism for selective operation of determined thread-guide rods, and for correlative pattern control mechanism selectively setting stops to regulate the traverse of the operating rods for either part or full course feeding movements.

It is recognized that attempts have heretofore been made to varyingly control the traverse of certain guide rods in successive reciprocations, 20 but such control has been limited and mainly for specific purposes of reenforcing or plating with added thread, while the present improvements are adapted for a wide variety of selective rod operations and varied traverse of each providing for heretofore impossible automatic production of an almost unlimited variety of fabric structures and designs through change of threads and color variation thereof, sectional fabric formation of determined outline and location, and 25 plated or reenforcing and embroidery areas of regular or ornamental figure structures.

The invention and its manner of application to and cooperation with a full fashioned knitting machine are fully described in the following specification in connection with the drawings accompanying the same and forming part thereof, and the novel features are clearly set forth in the appended claims.

Referring to the drawings which show only 40 such portions of a well known full-fashioned knitting machine structure as are sufficient to fully disclose the application thereto of one embodiment of the invention and its manner of operation,—

Fig. 1 is a fragmentary plan view of a central portion of a usual knitting machine, unessential portions being broken away or omitted, and showing a relative arrangement of the improved 50 means for selectively engaging determined thread guide carrier rods and for automatically controlling the feeding traverse of the same.

Fig. 2 is mainly an enlarged vertical cross sectional view of the machine, taken on the line 55 2—2 of Fig. 1, and more particularly showing

the mechanism for automatically selectively engaging determined thread guide carrier rods.

Fig. 3 is a partial rear sectional elevation taken substantially on the line 3—3 of Fig. 2.

Fig. 4 is a partial sectional plan view taken 5 substantially in the line 4—4 of Fig. 2.

Figs. 5 and 6 are detail sectional plan views taken respectively on the line 5—5 and 6—6 of Fig. 2.

Fig. 7 is a fragmentary detail elevation looking 10 in the direction of line 7—7 of Fig. 2.

Fig. 8 is an enlarged cross sectional view of one of the thread carrier rod engaging devices, the view being taken substantially on the line 8—8 of Fig. 3.

Fig. 9 is a detail sectional view taken on the line 9—9 of Fig. 8.

Fig. 10 is mainly an enlarged vertical cross-sectional view, similar to that of Fig. 2, but taken on the line 10—10 of Fig. 1, and showing more 20 particularly the automatic selective rod stop control mechanism.

Fig. 11 is a detail sectional plan view taken on the line 11—11 of Fig. 10 and showing the 25 selective connections to the several rod stop devices.

Fig. 12 is a partial sectional plan view taken on the line 12—12 of Fig. 10.

Fig. 13 is a similar partial sectional plan view, but taken on the line 13—13 of Fig. 10.

Fig. 14 is a rear sectional elevation, similar to Fig. 3, but taken on the line 14—14 of Fig. 10.

Fig. 15 is a perspective view of one of the rod stop slide plates, and Fig. 16 is a side elevation of the same and its housing, the view being taken 35 on the line 16—16 of Fig. 10.

Fig. 17 is a fragmentary cross sectional detail view of the idle course operating mechanism; and Fig. 18 is a fragmentary cross sectional view of other parts of said mechanism, the cross section 40 being taken at a different longitudinal portion of the machine.

The knitting machine indicated in the drawings is of the usual multi-section type, and its general construction and operation are well understood and need no particular description other than will appear in connection with that setting forth the present improvements, which latter involve little material change in the known machine functions, but add mechanisms particularly directed to the automatic pattern controlled selective feed operation of the several threads employed, as will now be fully described.

In full fashioned knitting machines, as well known, the feeding of the threads is effected by 55

a series of guide rods each carrying a plurality of thread guide fingers, one for each needle section, and motion being imparted to selected rods from a common friction box rod operated by the 5 usual coulier motion mechanism. The selection of a desired rod has commonly been determined by manual connection of such rod to one of the series of friction boxes on said friction box rod, and control of said guide rod movements commonly limited by stops engaging the same after 10 determined movements thereof, and special stops being required to be set when sectional fabric or plated areas are to be produced, all such setting movements heretofore being commonly manually effected by the operator prior to starting machine operation or during a determined halt in the latter.

The present improvements provide for the full automatic pattern controlled performance of all 20 such required selecting and setting operations, avoiding omission of any one, or wasteful machine delays, greatly increasing production, insuring against errors, and requiring less skill and attention of the operator.

25 To provide means for automatically selecting determined carrier rods for operating action, the construction shown in the drawings comprises the substitution for the heretofore commonly employed friction boxes, of a series of friction clutch devices A, one being preferably provided for each of the eight carrier rods 5 indicated, so that any selected rod may be automatically operated when desired.

The carrier rods 5, as heretofore, are longitudinally movably mounted in frame carried brackets 6, and each is shown as preferably provided with a section of rack teeth 7 for reciprocatively traversing the same. Only one end stop unit for the carrier rods is shown with the mechanism. It is to be understood that an identical unit is also necessary at the right hand end of the machine, Fig. 1. The carrier operating rod 8, reciprocatively traversed as heretofore by the usual coulier motion mechanism through connection to slur cock bar 8a, is also shown preferably provided with rack teeth 9. And each clutch device A is shown provided with a gear wheel 10 in constant mesh with the rack teeth 9 of rod 8, and a gear wheel 11 in constant mesh 40 with the rack teeth 7 of its respective carrier rod 5. The gear wheels 10 and 11 as indicated are connected by suitable frictional clutch mechanism, and it will be readily seen that by determined operation of such clutch means as hereinabove described, selective operation of any carrier rod 5 is simply provided for.

As more clearly shown in Fig. 8, each clutch device A comprises a housing 15, which, contrary to the heretofore employed friction boxes, does not shift its position, and is fixedly supported on a rigid frame rod 16 so as to overhang the series of carrier rods 5 and rest on a bracket 6 as indicated and each housing 15, as shown, is formed with suitable bearings for a shaft 17 for its respective gears 10 and 11, gear 10 being preferably keyed to said shaft and gear 11 freely rotatable thereon in the path of its particular guide rod 5, and properly spacedly retained in such position by a collar 18 fixed to shaft 17. The particular 65 frictional clutch mechanism indicated in the drawings as connecting gears 10 and 11, comprises a flanged brake drum 19 carrying adjustably tensioned spring-backed clutch-plates 20 in frictional engagement with gear 11, said drum 70 and clutch-plates being freely rotatable on shaft 75

17 except as engaged by an expanding brake ring 21, and said brake ring, as shown, lies within drum 19 and is carried by a collar 22 keyed to shaft 17 adjacent gear 10, a projectable wedge block 23 mounted in said collar being adapted to enter a split in brake ring 21 to expand the latter and lock said drum 19 to collar 22 and thus jointly rotate them, and consequently jointly rotate gears 10 and 11, except when rod 5 contacts with a fixed stop to limit its traverse movement 10 when gear 11 will be held against rotation and the clutch plates 20 will idly slip.

To determinedly project wedge block 23, shaft 17 is shown as having a central aperture in one end thereof to receive an axially shiftable pin 24, 15 the inner end thereof having a bevel-connected reduction 25, and said shaft 17 having a recess through which wedge block 23 extends, the latter being projected when riding on the larger diameter portion of pin 24 and being withdrawn 20 from projection to free brake ring 22 when riding on pin reduction 25. Pin 24 is shown as projecting beyond the end of shaft 17, and formed with spaced collars 26, 26 between which the forked ends of a lever 27 engage to axially shift said pin. 25 Lever 27 is fixed to a shaft 28 to which shaft is secured a pattern-actuated arm 29, and a hand lever 30 for manual engagement and disengagement of any particular rod 5 when desired. A spring catch 31 may be provided to hold pin 24 30 in desired position.

Each clutch device A as indicated is provided with its own particular lever 29, and each of said levers is operated by its particular one of a series 35 of rods 35 extending in spaced parallel relation to carrier rods 5 and mounted in suitable carrying brackets 36, and said rods 35 are selectively moved by suitable pattern controlled mechanisms hereinafter fully described, whereby automatic selection of any carrier rod is determinedly provided 40 for.

The particular pattern control mechanism for determinedly moving selected ones of rods 35 in either direction to connect or disconnect its respective clutch mechanism as above set forth, 45 comprises a series of levers 40, each having its forked end engaging between collars 41, 41 secured to its respective rod; said levers each being fixed to a particular one of a series of shafts 43, mounted in a suitable bearing bracket 44, as clearly seen 50 in Fig. 3. The opposite end of each shaft 43, as seen in Fig. 7, is provided with a crank arm 45, to which is pivoted one end of an arm 46, the other ends of the series of said arms being bent to converge and each respectively pivotally connected to one of a series of cross levers 47, all intermediately pivotally carried on a common axle 48 suitably mounted in bearing bracket 44. Located 55 below said axle 48, and lying in parallel spaced relation on opposite sides therefrom are two axles 49 and 50, each intermediately pivotally carrying a series of levers 51 and 52, respectively, with the inner ends of said levers overlapping in a medial line below axle 48, the drawings showing eight levers 51 and eight levers 52. The oppositely extending end of each lever 51 is shown connected by its separate link 53 to an end of its respective one of the series of levers 47, and the other ends of levers 52 are respectively separately connected by similar links 54 to said levers 47 on the side of 60 the latter adjacent arms 46. By appropriate action exerted on any one of the overlapping inner ends of levers 51 and 52 motion may be imparted to a determined lever 47, lever 51 swinging it to move its arms 46 upward, and lever 52 to move 65 70 75

its arm 46 downward. Such upward and downward movement of arms 46 it will be seen reversely move the respective shaft 43 to which said arm is connected so as to turn the latter and consequently swing its opposite end lever 40 in one or other direction, such action moving its determined rod 35 in one or other direction, which movement as above set forth engages or disengages the clutches of the respective devices A.

10 To selectively operate any one or more of said overlying inner ends of levers 51 and 52, the drawings show a row of push bars 55 slidably mounted in a frame 56 so as to lie in a vertical plane directly beneath said inner ends, the drawings indicating seventeen of said bars 55, sixteen acting individually on the sixteen inner ends of levers 51 and 52, and the seventeenth controlling a movement hereinafter set forth through a special bell crank 57 (Figs. 2 and 6) mounted on axle 49, and having one end 58 thereof, similar in shape to the inner ends of levers 51, extending above said seventeenth push bar 59.

To automatically selectively actuate any of the push bars 55 and 59, the drawings show a pattern chain 60 made up of pivotally connected sections of a width sufficient to embrace the row of seventeen bars 55, the selective movement of the latter being effected by properly placed pins 61 spacedly fixed to determined chain sections. This chain is carried by a drum 62 and its necessarily extended length is carried over idler drums or rollers 63, 64, 65, 66 and 67 adjustably mounted in suitable supporting arms of a chain carrier bracket 68 fixed to the knitting machine frame.

35 Drum 62 is shown carried by a shaft 70 mounted in the depending ends of a pair of links 71, 71, the other ends of which are pivotally connected to the ends of a pair of levers 72, 72 fixed to a shaft 73 mounted in frame carried bearings 74, 74. Shaft 73 is indicated as determinedly rocked by a lever 75 fixed thereto and having its free end provided with an anti-friction roller 76 riding on a suitably shaped cam 77 provided on the knitting machine main cam shaft 78, a spring 79 holding said roller 40 against said cam 77. Cam 77 acts to rock shaft 73 and thus raise and lower drum 62, carrying the pins 61 of chain 60 into contact with determined ones of push bars 55 to move the latter into action against their respective lever ends 51 or 45 52, which latter, as above set forth reversely shift rods 35 and these in turn selectively control the engagement and disengagement of the clutches of the respective devices A to operate a selected rod 5.

55 To determinedly rotate pattern chain 60 step by step, a ratchet gear 80 is shown secured to drum 62 and a pawl 81 is pivotally hung intermediate from a link 82, which link has one end pivotally connected at 83 to a fixed arm 84 and its other end pivotally connected at 85 to one of said links 71. The raising and lowering movement of link 71 will act at each reciprocation to rack gear 80 and thus bring a new chain section into operation against push bars 55 at each upward movement of drum 62. Pawl 81 is shown provided with an angular arm 86 adapted to engage with a suitably placed chain pin 61, whereby said pawl at a determined time is thrown out of engagement with gear 80 to stop the aforesaid rotation of the pattern chain. A hand lever 87 is also shown, carrying a spring pressed pawl 88 whereby gear 80 may be racked when desired to move pin 61 from beneath arm 86 to release the pawl 81 for resumed action on gear 80; said hand lever carried pawl 88 as shown also acting

as a reverse movement locking pawl for ratchet gear 80. Pattern chain pin 61 may be set to act at the end of a cycle of movement of said chain, or several may be employed to interrupt the chain action for long continued repetition of a fixed selected rod operation or such chain halting may be desirably employed for other special purposes of halting the machine operation for certain adjustments or for resetting of certain non-automatic controls.

10 At times it is desired to make so-called idle courses as heretofore and well understood to return the slur-cock bar 8^a to its idle position after completion of certain courses, and provision is made for automatically effecting such idle 15 courses as shown in the drawing by employing a suitably set chain pin 61 to determinedly act on push bar 59 which actuates the end 58 of bell crank 57 to swing the latter. Bell crank 57 as clearly shown in Figs. 2, 4, 17 and 18 is connected by a rod 98 to one end of an intermediately pivoted lever 91 the opposite end of which is formed with a cam foot 92 adapted to engage the angular extension of a spring tensioned catch lever 93 and turn the latter on its pivot 94. Lever 25 93 has a projection (not shown) acting as a catch to normally lock a lever arm 95 in depressed position against action of its spring 96 normally tending to swing said lever in a reverse direction, said lever 95 having an extension beyond said 30 catch lever engagement adapted to bear against a fixed projection on axially shiftable rod 97. The opposite end of lever 95, as indicated when released by catch lever 93 moves into the path of action of a compound cam 98 on cam shaft 78, 35 said cam then acting to swing said lever 95 on its pivotal support and also swing it in a plane at right angles thereto to longitudinally shift rod 97. The shifting of rod 97 shifts the cam operating needle-presser lever 98' to the action of 40 a different cam path on its operating cam 99 which different cam path will prevent needle beard-closing movement of presser lever 98', and furnish an idle course movement of a carrier rod at certain times necessary and understood in 45 the art.

The mechanism above fully set forth, provide for the automatic pattern-controlled selective operation of any desired thread-carrier rod 5, and while it has been thought essential to fully illustrate and describe the means for accomplishing this purpose, the specific structure disclosed forms the subject matter of a separate application filed June 3, 1930 by Max Richter, Serial No. 459,098.

To accomplish my aforesaid stated purpose of 55 providing full automatic selective pattern-controlled operation of the feed traverse of the several threads employed, additional automatic pattern-controlled mechanism is required to varyingly stop the traverse of any rod that may be 60 thus selectively operated. And while it is true that the above described mechanism may alone be considered a complete operative unit capable of certain limited automatic action with known fixedly set rod stops or known stops of limited 65 variation, or for more varied use where pattern chain pins are employed to interrupt continuous machine operation as previously set forth, my aforesaid rod operative mechanism essentially calls for correlative mechanism equally automatically operative to control the feed traverse of such rods in order that the full possibilities of such rod operation may be utilized in economical continuous operation of the knitting machine.

To provide such desired correlative means for 75

automatically controlling the thread feeding traverse of the several guide rods 5, automatically selectively engaged to function as above fully set forth, the particular means shown in the drawings comprises duplicate devices B, B, Fig. 1, one acting to stop rods moving to the right, and the other to stop rods moving to the left. As these devices, outside of their action as right or left stops, are identical in construction and operation, 10 a description of one will suffice for both.

Referring particularly to Figs. 10 to 17, control stopping of the rods 5 is shown as effected by a series of slide stop plates 100, each having an angularly stepped edge 101 adapted to engage 15 dogs 102 spacedly fixed to the respective carrier rods; and each plate being preferably split or forked so as to straddle its respective rod in moving up and down across the same so that a particular step of edge 101 may be positioned to 20 engage its respective rod dog 102. A series of eight slide stop plates 100 are shown in the drawings, one to act respectively on each of the eight carrier rods 5 indicated, and are mounted to slide vertically in a housing 103 held in suspended 25 position overhanging said guide rods by a bracket 104 carried on rod 16 and fixedly retained by a frame secured bracket extension 105. Individual selective positioning of each slide is effected, as shown, by means of an integral eccentric pin or 30 stud 106 projecting laterally therefrom through a vertical slot in the housing wall, four such pins from four of the slides projecting through one housing wall and four from the other slides projecting through the opposite housing wall, such 35 arrangement permitting desirably close assembly of a series of operative levers 107 having their forked ends engaging the projecting ends of the several pins 106, which latter are of stepped length for this purpose, as shown. The series of 40 levers 107 have a common pivotal support on a rod 108 mounted in extensions 109 of bracket 104, and each lever is intermediately pivotally connected to its respective one of a series of pattern actuated bell cranks 111 by a connecting link member 45 110.

From the description thus far advanced, it will be readily understood that by proper selective variable movement of any of the bell cranks 111, the respective slide plate 100, actuated thereby 50 through the mechanism above fully set forth, will be positioned vertically in the path of travel of its particular guide rod 5, so that a determined step of its inclined edge 101 will engage a fixed dog 102 to stop the travel of its respective rod 5 at such step position. By varying the extent 55 of movement imparted to bell crank 111, any selected step of edge 101 may be determinedly positioned. And it will furthermore be clear that the single point of variance of devices B, B, thus 60 far set forth, is in the direction of incline of their respective slide plates 100, the inclined edges 101 of which are opposed so that one will act as a right hand stop and the other as a left hand stop for the series of rods 5. These opposed sets of 65 slide plates 100, as above described, may readily perform all the required control regulations of the carrier rods, or they may be employed to act as supplemental rod controls adding additional automatic controls to the usual machine rod stops 70 heretofore provided and employed in well known manner, such automatically variable control acting in conjunction with automatic selective operation of the carrier rods heretofore set forth, providing for a multiplicity of automatically correlated thread feeding movements of part or full 75

course traverse during continuous automatic machine operation and the production of an almost unlimited variation of fabric structure and ornamentation and combinations thereof.

To automatically control the determined movements of the aforesaid bell cranks 111, the drawings show similar pattern chains 115 for the dual devices B and B, the following description of one such pattern chain mechanism sufficing, as they are essentially identical in construction and 10 operation.

The drawings show eight bell cranks 111, the chain actuated ends 112 of which lie in closely spaced relation, actuating the eight slide plate positioning levers 107, a ninth bell crank 113, has 15 a vertical instead of horizontal arm, actuating mechanism hereinafter more fully described.

The pattern chain 115 as shown, is made up of pivotally connected sections of a width sufficient to embrace the row of nine bell cranks 111 and 20 113, and carries properly placed pins 116, this chain being similar in construction to pattern chain 60 except that the pins 116 are of differing length to impart varying movements to said bell cranks as required to vary the position of slide 25 plates 100. This chain 115 is carried by a drum 117 and its extended length supported on idler drums or rollers 118, 119, 120, 121, 122, 123 and 124 adjustably mounted in suitable supporting 30 arms of a carrier bracket 125 fixed to the knitting machine frame.

Drum 117 is provided with a coaxial ratchet gear wheel 126 and is rotatably carried on axle 127, which axle is mounted to slide horizontally 35 in a slotted bearing 128 formed in an extension of fixed bracket 125. To the projecting ends of axle 127 are pivotally secured the forked ends of an actuating arm 129, the opposite single end of which is pivotally connected to the end of a lever 130, fixedly mounted on shaft 131 carried in 40 extensions 132 of bracket 125. A second lever 133 fixed to said shaft 131 carries at its end an anti-friction roller 134 adapted to ride on a suitable cam 135 on the main cam shaft 18 of the knitting machine. Motion imparted by said cam 135 will 45 move chain drum 117 from and toward the series of bell crank ends 112, and the chain pins 116 will variously move them at each drum reciprocation. A racking movement is imparted to drum 117 by means of a pawl 136 pivotally carried at one end 50 of a lever 137 intermediately pivoted on drum axle 127 the other end of lever 137 having a hand actuating rod 138 for manually racking said drum, and a spring 139 normally tending to move said lever 137 to the right. Pawl 136 is held in 55 engagement with ratchet gear 126 by means of a spring 140, and a catch arm 141 intermediately pivotally supported on lever 137, is held against a fixed stop 142 by spring 143. At each advancing movement of drum 117 spring 139 moves lever 137 60 to position pawl 136 to engage an advanced tooth of ratchet gear 126, and at each return movement of said drum, fixed stop 142 engages catch arm 141 to move lever 137 against the tension of its spring 139 and thus cause pawl 136 to rack 65 said drum to bring new pins 116 into action at the next drum reciprocation. A suitable detent may be provided to prevent unintentional reverse movement of drum 117.

Duplicate devices B, B, are employed as previously stated, as right and left stops for the thread carrier rods 5, and it will be readily understood that their respective pattern control chains 115, for most effective results, should act during movement of said guide rods in one direction only 75

and remain idle during reverse rod movement. Cam shaft 78 however commonly makes one complete rotation during movement of a carrier rod in one direction, and its cam 135 would therefore 5 act to unnecessarily oscillate said chain drum during reverse rod movement and necessitate burdensome double length of the pattern chains. To avoid such unnecessary cam action, the drawings show shaft 78 as carrying a concentric disc 10 150 adjacent cam 135, upon which friction roller 134 is moved to idly ride during such reverse rod movement. As best seen in Figs. 10, 13 and 14, slur-cock bar 8^a movable jointly with carrier operating rod 8, is indicated as carrying two fixedly 15 secured spaced contact blocks 151 and 152, block 151 engaging and swinging a lever 153 at the end of said rod movement in one direction, and block 152 engaging and oppositely swinging the same lever 153 at the end of reverse rod movement. 20 Lever 153 is shown as secured to a shaft 154 having a crank arm 154^a pivotally carrying a link 155, said link having a tensioning spring 156 normally holding its notched end 157 in engagement 25 with a pin 158 on crank 159 carried by a shaft 160. Shaft 160 is mounted in suitable bearings and carries a lever 161 engaging with friction roller 134, the latter having a limited lateral movement in its mounting on lever 133. The action 30 of rod block 151 engaging and swinging lever 153 will be to effect, through the aforesaid connection, a turning movement to shaft 160 causing the arm 161 of the latter to shift roller 134 from cam 135 to concentric disc 150. Rod block 152, by 35 engaging lever 153 will oppositely move the latter and consequently reversely shift roller 134 so as to again ride on cam 135. It will be understood that the slur cock bar 8^a will carry two other contact blocks similar to blocks 151 and 152 40 adapted to act on the corresponding lever 153 of the similar control mechanism for the other one of the duplicate devices B, B, so that the pattern chain drums 117 of said similar devices will operatively reciprocate once for each two rotations of 45 cam shaft 78.

To automatically stop the pattern chains 115, as at the end of a complete rotation thereof, or intermediately thereof for any desired purpose, a chain pin may be readily set to engage bell crank 50 113 and cause the latter to bodily shift lever 170 on its pivot bearing rod 171 against the retractive action of spring 172, such shifted position of said lever 170 placing it in position for engagement with a suitable pin 173 on slur cock bar 8^a, to 55 swing said lever on its pivot 171. The opposite end of lever 170 carries a finger 174 engageable with the end of link 155 and movement of said lever 170 by said pin 173 causes finger 174 to swing link 155 to disengage its notch 157 from 60 crank pin 158, such disengagement taking place when roller 134 is riding on disc 150 and preventing shifting of said roller by the next action of block 151 on lever 153. When thus stopped pattern chain 115 will remain at rest irrespective of 65 continued machine operation until hand rod 138 is operated to free bell crank 113 from such pin engagement.

The mechanisms above fully described thus provides for full automatic pattern controlled 70 action of the feeding traverse of any of the component threads employed by selective operation of any guide rod 5 and by control of its traverse feed movement through selective setting of any stop plate 100. Variations and selected combinations of such control movements will automat-

ically produce almost any fabric variation desired and any reenforcing or ornamenting with added thread. Also sectional fabric may be produced with so-called closed or overlapping suture seams. Where open or so called "split foot" suture 5 seams are desired the drawings indicate provision for effecting this purpose by making eccentric the pivotal connection 180 of arm 129 and lever 130, and providing such pivotal connection with an arm 181 by means of which it may be turned. 10 The turning of such eccentric pivot 180 after lever arm 129 has been moved forward the full extent by action of cam 135 on lever 133, will cause an additional forward movement being imparted to chain drum 117 and consequently 15 additional movement of certain slide stop plates 100 permitting an additional feed movement to rods stopped by the first position of said plates 100. Such additional feed movement of the rods is effected after the knitting action of such course 20 and produces as well known in the art, an open suture seam commonly known as a "split foot" seam.

Determined turning movement of eccentric arm 181 is effected as indicated by a cam 185 on cam 25 shaft 78 acting on the anti-friction roller 186 of a lever 187 pivotally supported at 188. A second lever 189 on said pivotal support 188 is moved by lever 187 to turn arm 181 through connecting link 191. Anti-friction roller 186 is laterally shiftable 30 into and out of the path of cam 185, the drawings merely indicating a hand lever 190, as such movement is ordinarily for continued lengths of courses when employed at all, and therefore it is not essential to make it automatically operative, but 35 merely requires certain pins in the pattern chain to interrupt automatic operation for such hand setting. It is obvious however that such hand movement might be automatically effected if desired. 40

From the foregoing description it is believed the nature of the present improvements and their manner of operation will be readily understood, and while one form of embodiment has been shown and set forth in detail other forms and 45 modifications may be readily devised within the spirit of the invention as defined in the following claims.

What I claim is:—

1. In a straight knitting machine, a plurality 50 of movable carrier rods, end stops therefor, a plurality of independently operable auxiliary stops located between said end stops and each arranged to stop in individual carrier rod at varied points in its travel and automatic means including a pattern device for actuating each of said stops independently of the others.

2. In a straight knitting machine including a plurality of individual movable yarn carriers, yarn carrier driving means, a plurality of variably 60 actuating stop units located along the plurality of yarn carriers, each of said units comprising a plurality of similarly formed stop plates, one for each carrier, means operative to select a yarn carrier to be driven by said driving means, means 65 cooperating with, and operating in timed relation to said yarn carrier selecting means to select the corresponding stop plate, to effect a determined yarn carrier stroke.

3. In a straight knitting machine including a 70 plurality of movable carrier rods, carrier rod driving means, a plurality of stop units located along the carrier rods, each of said units comprising a plurality of similar stop plates each of which 75 is adapted to cooperate with one of the carrier

- rods, means operative to selectively connect one of said carrier rods to the carrier rod driving means, means operative to select the corresponding stop plates for the selected carrier rod to effect a determined carrier rod stroke, and common actuator means operating the selecting means in timed relation one to the other.
4. In a straight knitting machine including a plurality of individual movable yarn carriers, 10 yarn carrier driving means, a plurality of variably actuating stop units located along the plurality of yarn carriers, each of said units comprising a plurality of similarly formed stop plates, one for each carrier, means operative to select a yarn carrier to be driven by said driving means, means cooperating with, and operating in timed relation to said yarn carrier selecting means to select the corresponding stop plate to effect a determined yarn carrier stroke, said cooperating means including predetermined pattern control mechanism.
5. In combination with a straight knitting machine, automatic thread-traversing mechanical control mechanism comprising a plurality of movable thread carrier rods, separate operative mechanisms for said rods, means for selectively engaging a determined mechanism with its respective rod, separate rod stop devices for said rods each having a plurality of rod-engaging stops selectively movable into the path of its respective rod, means for selectively moving said stop devices to position determined rod stops of the latter, and cooperative pattern control mechanisms for said selective rod operating means, and for said selective rod stop positioning means.
6. In combination with a straight knitting machine, automatic thread-traversing mechanical control mechanism comprising a plurality of movable thread carrier rods, operative mechanism for selectively moving determined rods and for varying the feed traverse movement of said rods in successive knitting courses, pattern mechanism controlling the selective operative movements of determined rods and their varied 40 traverse movements, said pattern mechanism also controlling intermittent interruption of said selective operative movements.
7. In combination with a straight knitting machine, automatic thread-traversing mechanical control mechanism comprising a plurality of movable thread carrier rods, separate operative mechanisms for the several rods each having a frictional clutch engaging connection, means for selectively operating the respective clutch connections, separate stop devices for the several rods each having a plurality of rod-engaging stops selectively positioned by movement of its device to variably limit the feed traverse movement of its respective rod, means for selectively moving said stop devices, and cooperative pattern control mechanisms.
8. In combination with a straight knitting machine, automatic thread traversing mechanical control mechanism comprising a plurality of reciprocatively movable thread carrier rods, separate bifurcated stop devices overhanging the several rods each adapted to straddle its respective rod and movable vertically across the latter and each having a stepped angular edge, each step thereof forming a rod-engaging stop to variably limit the 55 traverse movement of its respective rod, and pattern mechanism controlling the automatic selective vertical movements of said stop devices to determinedly position selected steps of the latter.
9. In a straight knitting machine having a reciprocatively movable thread carrier rod, a rod stop control mechanism comprising a stepped-edge slide plate having aligned contact surfaces and located intermediate the ends of said rod and movable across said rod to position a selected step in the path of travel of said rod, and pattern control mechanism for selectively moving said slide plate.
10. In a straight knitting machine having a reciprocatively movable thread carrier rod, a rod stop control mechanism comprising a bifurcated stepped-edge slide plate adapted to straddle said rod and move across the same to position a selected step in the path of travel of said rod, and pattern control mechanism for selectively moving said slide plate.
11. In a straight knitting machine having a reciprocatively movable thread carrier rod, a rod stop control mechanism comprising a stepped-edge slide plate movable across said rod to position a selected step in the path of travel of said rod, a lever mechanism for slidably moving said plate, and a pattern chain having pins of varying height to variously operate said lever mechanism.
12. In a straight knitting machine having a plurality of reciprocable thread carrier rods, end stops therefor, adapted to control the throw of the rods carrying the body yarn, auxiliary rod stop control mechanism comprising a plurality of stepped-edge slide elements, intermediate the ends of each of said rods, variably movable to position any selected step thereof in the path of travel of the related rod, and pattern control mechanism for causing variable movement of any selected one of said elements to position a determined step thereof in operative relation to its respective rod.
13. In combination with a straight knitting machine, automatic thread traversing mechanical control mechanism comprising a plurality of reciprocatively movable thread carried rods, end stops therefor, separate stepped stop devices passing between the several rods intermediate the ends thereof and each reversely movable relative to and along a side of its respective rod to determinedly limit the traverse movement of the latter, and pattern mechanism selectively controlling said stop devices to effect varied movement of a determined stop device relative to its respective rod.
14. In combination with a straight knitting machine, automatic thread traversing mechanical control mechanism comprising a plurality of reciprocatively movable thread carrier rods, end stops therefor, a pair of stop devices intermediate the ends thereof, each device comprising a plurality of rod-engaging stepped stops adapted to pass between the carrier rods and arranged for varied movement in reverse directions to position a determined step in the path of said rod, said devices coacting to variably limit the traverse movement of the latter in both directions of its reciprocative movements, and pattern mechanism controlling said stop devices to cause variable movements thereof to position determined stops in the path of their respective rods.
15. In combination with a straight knitting machine, automatic thread traversing mechanical control mechanism comprising a plurality of reciprocatively movably thread carrier rods, end stops for said rods, additional stop devices for the several rods each having a plurality of rod-engaging stepped stops coacting with said end stops and selectively positioned by movement of its latter.

device to lie in the path of travel of its respective rod and adapted to pass between said rods to variably limit the traverse movement of the latter, and pattern mechanism controlling the 5 automatic selective movements of said stop devices to determinedly position selected stepped stops of the latter.

16. In combination with a straight knitting machine, automatic thread traversing mechanical control mechanism comprising a plurality of reciprocatively movable thread carrier rods, separate bifurcated stop devices for the several rods each adapted to straddle its respective rod and movable across the latter and each having a 15 stepped angular edge each step thereof forming a rod-engaging stop to variably limit the traverse movement of its respective rod, and pattern mechanism controlling the automatic selective movements of said stop devices to determinedly 20 position selected steps of the latter.

17. In combination with a straight knitting machine, automatic thread traversing mechanical control mechanism comprising a plurality of reciprocatively movable thread carrier rods, end 25 stops for said rods, a plurality of stop devices for the several rods each device having a plurality of rod-engaging stepped stops coacting with said end stops and selectively movable into the path of its respective rod and adapted to pass between 30 said rods to variably limit the traverse movement of the latter in one direction of its reciprocative movements, and pattern control mechanism for said stop devices controlling their independent selective movement to position determined rod-

engaging stops thereof in the path of traverse of their respective carrier rods.

18. In combination with a straight knitting machine, automatic thread traversing mechanical control mechanism comprising a plurality of reciprocatively movable thread carrier rods, separate stepped stop devices for the several rods with each stepped stop thereof positionable to limit the traverse movement of its respective rod, pattern control mechanism adapted to automatically move said devices to position selected steps thereof, and mechanism controlled by said pattern mechanism and adapted to move one step out of position after its rod stopping action and position a different step in position to effect 15 a delayed additional movement of the rod whereby a split-seam loop is formed.

19. In a straight knitting machine having a reciprocatively movable thread carrier rod, a rod stop control mechanism comprising a stepped- 20 edge slide plate movable across said rod to position a selected step in the path of travel of said rod, a lever mechanism for slidably moving said plate, an oscillating pattern chain controlling varied movements of said lever mechanism, a cam 25 actuated lever adapted to oscillate said pattern chain, and a chain controlled mechanism adapted to effect a delayed continuation of said cam actuated lever to additionally move said pattern chain in one oscillation whereby a different step is positioned after rod stop by another 30 step to effect a delayed additional rod movement.

RUDOLPH ANKE.
